UNITED STATES PATENT OFFICE.

CHARLES A. HOLM, OF TIGERTON, WISCONSIN.

SHARPENER FOR FEED-CUTTERS.

1,339,511.

Specification of Letters Patent. Patented May 11, 1920.

Application filed May 12, 1919. Serial No. 296,444.

To all whom it may concern:

Be it known that I, CHARLES A. HOLM, a citizen of the United States, and resident of Tigerton, in the county of Shawano and State of Wisconsin, have invented certain new and useful Improvements in Sharpeners for Feed-Cutters; and I do hereby declare that the following is a full, clear and exact description thereof.

10 My invention relates to improvements in feed cutters or similar machines having rotary comminuting blades, and more particularly to means for sharpening such blades during the normal operation of the machine 15 of which they form a part.

It is the principal object of this invention to provide sharpening means which may be readily associated with standard machines equipped with rotary blades, or incorporated 20 in such machines being built.

A further object is to provide a sharpening device which will have a relatively universal yielding movement with respect to the cutting blades so that excessive abrading will be 25 prevented, the blades being only sufficiently engaged to always retain them at their maximum sharpness.

A still further object is to provide an improved simply constructed holding clamp 30 for an abrading member.

With these objects in view and others which will become apparent as the description proceeds, my invention resides in certain novel features of construction, combination and arrangement of parts which will 35 be hereinafter more particularly described and claimed and shown in the drawing, in which:

Figure 1 represents a vertical longitudinal 40 sectional view through the discharge end portion of a feed cutter or the like.

Fig. 2 is a relatively horizontal sectional view through the guard portion of a feed cutter showing the improved sharpening device 45 vice in plan view, certain parts however, being in section.

Fig. 3 is a detail elevational view, partly in section, of the means for supporting one end of the sharpening device, and

50 Fig. 4 is a vertical sectional view of a modification of the invention, this form being adapted to be associated with feed cutters and the like which have already been placed in operation.

Referring to the accompanying drawing, 55 especially to Figs. 1, 2 and 3 thereof, it will be noted that I have depicted my invention in coöperation with a rotary knife 1 comprising radial blade carrying arms 2 and slightly helical cutting blades 3. This knife 60 1 is mounted on a transverse drive shaft 4 located at the discharge end of the feed cutter indicated broadly by the character F and journaled in bearings on the side bars 5 thereof. The type of knife illustrated is 65 similar to that used not only in feed cutters, but in many other machines, one of whose operations consists in cutting or chopping lengths of material into small bits, and therefore it will be appreciated that the invention 70 may be used on feed cutters and such other machines.

The form of the invention used in the construction in the figures above referred to is designed to be incorporated in the machine 75 during its manufacture and is therefore carried by a specially constructed guard-hood 6. It might be here mentioned that practically all standard feed cutters are provided with a guard-hood more or less similar to the 80 hood 6 for protecting the operator of the machine, such guard being located over the discharge chute to shield the knife during its rotation. The hood 6 has its bottom and inner side open and is secured by lateral 85 flanges 7 to the ends of the side bars 5 by bolts or the like 8.

The opposite side walls 9 of the hood are each provided with a slot 10 through which a pivot rod 11 extends. Each of the walls 90 9 adjacent the opening 10 therein is also provided with an outwardly projecting ear 12 through which a shank 13 of an adjustable bearing 14 extends. Said shanks are screw-threaded to receive adjusting nuts 15 95 disposed on each side of the ears 12.

The opposite ends of the pivot rod 11 extend through the openings in the adjustable bearings 14, and it will be noted that these openings are considerably larger than 100 the diameter of the rod and that resilient bushings 16 are disposed therein to form yieldable bearings for said rod. Nuts 17 on the opposite ends of the rod prevent the same from shifting longitudinally within 105 said bushings.

The pivot rod 11 is adapted to support a pair of spaced like abrading bar clamps 18,

each of which comprises a plate 19 having a pivot ear 20 disposed intermediate its ends for journally mounting the same on the rod; one end of the plate is shaped to form a 5 clamp jaw 21 for coöperation with a second clamp jaw 22. A bolt or the like 23 connects the two clamp jaws and retains them in coöperative position, the jaw 22 having a laterally extending finger 24 engageable 10 within a socket 25 on the plate 19 whereby the said jaw can more effectively perform its function.

The opposite end of the plate 19 from the 15 jaw 21 is longitudinally slotted as at 26 to receive a spring rod 27 that extends from the top wall of the guard-hood 6 and carries a pair of expansile springs 28 and 29, one of which is located on each side of the plate 19. The plate is thus urged to remain 20 in one position and when rocked in either direction about the pivot rod 11 it is returned to normal position when released.

The jaws of the two clamps 18 are designed to engage a pair of angle clamp 25 bars 30 between which an elongated bar 31 of abrading material is disposed. This bar 31 is so adjusted with respect to the cutting edges of the blades 3 by means of the adjustable bearings 14 and adjusting nuts 27' 30 on the ends of the spring rods 27 that it will be successively engaged by said blades as the knife is rotated. As hereinbefore set forth the abrading member has a substantially universal yielding movement with respect to the blades 3 and from the foregoing 35 described structure it will be obvious that this is procured as a result of the resilient mounting of the pivot rod 11 and the springs 28 and 29. The resilient bushings 16 for 40 the pivot rod 11 allow the latter, and consequently all of the parts carried thereby, to yield away from the rotary knife whenever either of the blades 3 thereof strike against the bar 31; the pivotal connection of the 45 clamp 18 with the pivot rod 11 permits the abrading member to be urged in the direction of movement of one of the blades 3 when engaged thereby.

I have attained similar movements of the 50 abrading bar 31' shown in Fig. 4 in a manner slightly different from that just described. The form of the invention illustrated in this figure is designed to be associated with a feed cutter or the like which 55 has already been placed in operation, such machine being equipped with a standard guard hood 6' detachably secured to the ends of side bars 5' by means of bolts 8'. Normally the end walls 9' of the hood 6' 60 are in flush engagement with said ends of the side bars 5', but in mounting my invention on said hood, the latter is spaced from said ends of the side bars 5' by resilient washers 35. Likewise similar resilient washers 36 are disposed between the nuts 8" of

the bolts 8' and the attaching flanges of the hood.

Each of the clamps 18' used in this form of my invention consists of a plate 19' having a clamp jaw 21' and a socket 25'. The 70 coöperating clamp jaw 22' of the first mentioned jaw has a finger 24' disposed in said socket 25', the abrading bar 31 being secured between said jaws 21' and 22' and clamp bars 30' by bolts 23'. The end of the 75 plate 19' opposite the jaw 21' is apertured to receive the shank of an attaching bolt 37 that extends through an opening in one wall of the hood 6' adjacent its lower edge. A nut 38 threaded on said shank secures the 80 blade to the hood, a resilient washer 39, however, being interposed between the wall of the hood and the plate 19' before applying said nut 38.

In this form of the invention the yielding 85 of the abrading member 31 in the direction of travel of one of the blades 3 is permitted by the resiliency of the washers 39 while said bar is permitted to be urged away from the blades when struck thereby by the resilient washers 35 and 36. The resilient nature of these washers, 35, 36 and 39 act similarly to the resilient bushings 16 and the 90 springs 28 and 29 and return the parts to normal position when engagement between 95 the several blades 3 and the abrading member 31 no longer exists.

The preceding description setting forth the several forms of the invention readily shows that various changes may be made in 100 my idea without departing from the important features thereof or sacrificing any of the advantages.

I claim:

1. In a device of the class described, a 105 member adapted to be engaged by a movable cutting blade, and yieldable supporting means for the member, said member being urged in two different directions by the engagement of the blade.

2. In a device of the class described, a member adapted to be engaged by a movable cutting blade, and yieldable supporting means for the member, said member being simultaneously urged in two different directions by the engagement of the blade.

3. In a device of the class described, a member adapted to be engaged by a movable cutting blade, and yieldable supporting means for the member, said member being urged in a line of direction substantially tangentially of the path of movement of the cutting blade and in a line of direction substantially at right angles to said path.

4. In a device of the class described, a member adapted to be engaged by a rotary cutting blade, and yieldable supporting means for the member, said member being urged in a line of direction substantially 125

tangentially of the path of movement of the cutting blade and in a line of direction substantially diametrically of said path.

5. In a device of the class described, a lever, a shiftable pivot for the lever, and a contact member carried by the lever and adapted to be engaged by a cutting blade, said contact member defining orbital and rectilinear movement when engaged by the

10 blade.

6. In a device of the class described, a support, a lever pivoted intermediate its ends, a yieldable bearing carried by the support and receiving the pivot of the lever, a spring engaged with one end of the lever and resisting orbital movement of said end in either direction, and a contact member on the other end of the lever adapted to be

engaged by a cutting blade, said member being shifted orbitally and rectilinearly 20 when engaged by the blade.

7. A clamp comprising a supporting plate having a socket, one end of said plate forming one jaw member, a second jaw member for coöperation with the first, a finger extending from the second jaw member and removably disposed in said socket, and a connecting member joining the two jaw members for drawing the same together to clamp an article therebetween. 25

In testimony that I claim the foregoing I have hereunto set my hand at Tigerton, in the county of Shawano and State of Wisconsin.

CHAS. A. HOLM.
